DESIGN FOR A WATCH CHARM OR SIMILAR ARTICLE

Orville S. Hull, Jr., Jefferson City, Mo.

Application September 11, 1943, Serial No. 111,101

Term of patent 14 years

To all whom it may concern:

Be it known that I, Orville S. Hull, Jr., a citizen of the United States, residing at Jefferson City, in the county of Cole and State of Missouri, have invented a new, original, and ornamental Design for a Watch Charm or Similar Article, of which the following is a specification, reference being had to the accompanying drawing, forming part thereof.

Fig. 1 is a perspective view of a watch charm or similar article showing my new design.

Fig. 2 is a side elevation of the watch charm.
Fig. 3 is a front elevation of the watch charm.
Fig. 4 is a side elevation showing the watch charm from the opposite side from Fig. 2.

Fig. 5 is a bottom view of the watch charm.
I claim:

The ornamental design for a watch charm or similar article, as shown.

ORVILLE S. HULL, JR.
